UNITED STATES PATENT OFFICE.

FRED H. KNAPP AND CLARENCE W. BLACKSTONE, OF CHICAGO, ILLINOIS,
ASSIGNORS TO THE FRED H. KNAPP COMPANY, OF CHICAGO, ILLINOIS,
A CORPORATION OF ILLINOIS.

LABELING-MACHINE.

SPECIFICATION forming part of Letters Patent No. 724,715, dated April 7, 1903.

Application filed January 25, 1902. Serial No. 91,154. (No model.)

To all whom it may concern:

Be it known that we, FRED H. KNAPP and CLARENCE W. BLACKSTONE, citizens of the United States, residing at Chicago, in the county of Cook and State of Illinois, have invented new and useful Improvements in Labeling-Machines, of which the following is a specification.

Our invention relates particularly to can-labeling machines of the general construction shown in Patents No. 548,866, October 29, 1895; No. 561,656, June 9, 1896, and No. 612,825, October 25, 1898.

Our primary object is to provide an improved label-receptacle for machines of this character, improved means for operating the label-follower employed in connection with said receptacle, and improved means for preserving the vertical alinement of the rear edges of the labels in the receptacle.

As is well understood, machines of the character referred to are provided with longitudinally-extending runways or guides for the cans to travel in, an endless belt or conveyer located above the runway and having a rearwardly-traveling lower portion engaging the upper portions of the cans, a paste-applying roll over which the cans pass near the feed end of the machine, and a label-receptacle located in the rear of the paste-applying roll and having its upper margin flush with the guides upon which the cans travel, said receptacle being provided with a follower, which serves to elevate the labels, so that they shall come in succession to the level of said guides, there to be engaged by the cans on their passage through the machine.

Our invention is illustrated in its preferred embodiment in the accompanying drawings, 40 in which—

Figure 1 represents a broken side elevational view illustrating the central portion of a machine with our attachments applied thereto; Fig. 2, a broken central longitudinal section of the bottom of the runway in the rear of the label-receptacle and showing a label-stop employed; Fig. 3, a transverse section taken as indicated at line 3 of Fig. 2; Fig. 4, a spring employed in connection with the label-stop; Fig. 5, an enlarged vertical section

taken as indicated at line 5 of Fig. 1, the ratchet-wheel and attendant parts not being shown in section; Fig. 6, a fragment of one side of the label-receptacle; Fig. 7, a perspective view of a rock-lever employed, and Fig. 8 a side elevational view of ratchet mechanism employed.

A represents the upper longitudinal frame members of a can-labeling machine; A', the lower longitudinal frame members thereof; B, the runway, having a yielding side piece *a* of well-known construction; B', a conveyer-belt, the lower portion of which is engaged and dished downwardly by suitably-fashioned rolls *b* for the purpose explained in Patent No. 561,656; C, a label-receptacle; D, a label-stop arranged at the rear end of said label-receptacle; E, a label-follower constituting, in effect, a movable bottom for the label-receptacle C and carried by a stem E', equipped at its lower end with a rack E²; E³, a depending bracket supported from a cross member E⁴, having arms E⁵, connected with the upper portions of the longitudinal frame members A'; E⁶, a horizontally-disposed shaft journaled in bearings E⁷, connected with the lower end of the bracket E³; E⁸, a pinion on said shaft and engaging the rack E²; E⁹, a ratchet-wheel fixed to said shaft and serving to rotate the same; E¹⁰, an arm journaled on the shaft E⁶ and equipped at its outer end with a pawl E¹¹, engaging the teeth of the ratchet-wheel; E¹², a connecting-rod, through the medium of which the arm E¹⁰ and its pawl are actuated; E¹³, a stationary arm equipped with a pawl or dog E¹⁴, which serves to prevent retraction of the ratchet-wheel; E¹⁵, a pawl-releasing device journaled on the shaft E⁶ and provided with arms c c', equipped with pins c² c³, respectively, engaging the inner sides of the pawls E¹⁴ E¹¹, respectively, said device E¹⁵ being further provided with an actuating-handle c⁴; F, a can-actuated rock-arm provided with a slot f, with which the upper end of the rod E¹² is connected; G, Figs. 2 and 3, a bottom section for the runway B, located in the rear of the label-receptacle; G', a slide connected therewith and forming a part of the label-stop D; G², a label-engaging finger carried by said slide; G³,

a spring connected with the bottom piece G and serving to yieldingly hold the slide G', and H a tension device of well-known construction, which engages the rear portion of the uppermost label.

The direction of travel of the conveyer-belt is indicated by the arrow in Fig. 1, and a can g is shown in dotted lines to clearly indicate the course of the cans through the machine.

10 The upper portion of the receptacle C forms, in effect, a part of the bottom of the runway for the cans.

The receptacle C has its end nearest the slide G' open, thereby exposing the ends of the labels against which the tappet-operating portion G² of the slide operates, and is provided with an adjustable side h, carried by angle-irons h', whose horizontal portions rest on the arms E⁵ at that side of the machine

20 and move in guides h². Connected with the member E⁴ is a bracket h³, with which a bolt h⁴ has threaded connection, said bolt being provided with a lock-nut h⁵ and having connection at its inner end with the side h, which

25 it serves to adjust. The rock-arm F is connected with the upper portion of the side plate h by a pivot k, having an inwardly-projecting end formed with a knife-edge k', the latter serving to engage the adjacent edge of the uppermost label.

30 The lever F is provided at its front end with an inwardly-projecting lug k² and at its rear end with an inwardly-projecting lug k³, the former moving in a recess k⁴ and the latter in a recess k⁵, with which the side h is provided. A spring k⁶, Fig. 6, supported by a lug k⁷, Fig. 5, serves to resist depression of the front end of the lever F. When a can passes over the top of the label-receptacle, it first engages the front end

40 of the lever F (assuming an elevation of the labels to be required) and depresses the same, thereby raising the rear end of said lever and lifting the connecting-rod E¹² to cause the pawl E¹¹ to engage a new tooth on the

45 ratchet-wheel. As the can continues its movement the uppermost label adheres to the can and is wrapped thereupon, and after the can passes the pivotal point of the lever F it serves to depress the rear end of said

50 lever, thereby actuating the pawl E¹¹ and moving the ratchet-wheel E⁹ in the direction indicated by the arrow in Fig. 1. The effect is to raise the follower E, through the medium of the rack E², a distance corresponding to the thickness of several labels, and thereafter the lever makes only short or ineffective oscillations till the labels are used sufficiently to permit the can to depress the lever the full working stroke.

60 Opposite the side h is an adjustable side l, supported on angle-irons l', having horizontal members l², resting on corresponding arms E⁵ of the member E⁴. The members l² move in guides l³, the latter being equipped with standards or spring-retainers l⁴, bearing inwardly-projecting studs l⁵, receiving springs l⁶, confined between the members l² and the

outer surface of the side l. Located centrally of the length of the receptacle is a bracket l⁷, supported from the members E⁴ and provided at its upper end with a perforation, which loosely receives a bolt or stud l⁸, having its inner end secured to a boss on the outer surface of the side l. The outer end of the stud l⁸ is threaded and equipped with a washer l⁹ and a hand-wheel or manually-operated nut l¹⁰. The sides of the receptacle are adjusted to hold the labels accurately, and the construction is such that the side l may be readily moved to permit a fresh supply of labels to be introduced into the receptacle. After the labels are introduced the nut l¹⁰ is unturned, allowing the springs l⁵ to force the side l inwardly against the adjacent edges of the labels. Thereafter the nut is given a slight turn to the right to slightly relieve the pressure of the side plate upon the labels.

In Fig. 1 the upper front portion of the side plate l is shown equipped with a short rock-arm m, spring-actuated in one direction by a spring m' and actuated in the other direction by a can passing over the front end of the receptacle. The arm m is supported at its rear end by a pivot m², journaled in the side plate l and having a knife-edge m³ engaging the uppermost label.

As shown in Figs. 2 to 4, inclusive, the spring G³ is connected at its rear portion with the plate G by means of a staple n and has at its front portion two inwardly-projecting ends n', which connect with lugs n², with which the slide G' is provided. The finger G² has a forwardly-projecting point n³, which projects over the rear margin of the uppermost label, and it has also a vertical portion n⁴, which engages the rear edges of the uppermost labels and serves to keep the same in proper alinement.

The operation will be readily understood by those skilled in the art. Cans are fed into the machine in the usual manner and automatically spaced by the machine so as to follow each other in regular order, and in passing over the label-receptacle they pick up the labels one by one, each can alternately actuating the rock-lever F (effectively or ineffectively) in one direction and then in the other, thereby to cause the follower E to be positively moved upwardly by successive steps as a fresh supply of labels is needed. After the follower E has been fed to the top of its traverse the pawl-releasing device E¹⁵ may be moved through the medium of the handle c⁴, thereby raising the pawls E¹⁴ and E¹¹ and permitting a reverse movement of the ratchet-wheel E⁹, the follower falling down of its own weight.

As each can passes over the labels, one label is wrapped upon it, the slide G' yielding somewhat at the passage of the can and under the reaction of its spring acting as a tapet to restore the rear edges of the top labels to vertical alinement. The tip n³ of the fin-

ger G² may yield somewhat vertically also, owing to its springy nature. Thus the top-most label is held under light pressure at its rear margin, but is readily withdrawn during the passage of the can:

Changes in minor details of construction within the spirit of our invention may be made. Hence no undue limitation is to be understood from the foregoing detailed description.

What we regard as new, and desire to secure by Letters Patent, is—

1. In a machine of the character described, a label-receptacle, a lever pivotally connected therewith and having can-engaging means located on opposite sides of its pivot, a connecting-rod actuated by said lever, a label-follower, and follower-actuating means actuated by said connecting-rod.
2. In a machine of the character described, a label-receptacle having a movable bottom constituting a follower, a movable side plate supported by members moving in suitable guides, stationary spring-retainers located near the ends of said plate, springs confined between said retainers and the outer surface of said plate, a centrally-located threaded stud connected with said plate, a stationary bracket provided with a perforation through which said stud extends, and a nut on the outer end of said stud.
3. In a machine of the character described, a label-receptacle and a suitably-actuated la-

bel-follower, in combination with a slide longitudinally reciprocable with reference to the bed, a spring serving to yieldingly hold said slide, and a stop carried by said slide and serving to engage the rear portions of the uppermost labels.

4. In a machine of the character described, the combination of a label-receptacle, a rock-lever pivotally connected therewith, having inwardly-projecting lugs located on opposite sides of its pivot, with the label-follower, and means for raising said follower positively actuated by said rock-lever.

5. In a machine of the character described, the combination of a label-receptacle, a lever pivotally connected therewith and having can-engaging means located on opposite sides of its pivot, with a label-follower provided with a rack, a shaft equipped with a pinion engaging said rack, a ratchet-wheel serving to operate said shaft, an arm journaled on said shaft carrying a pawl engaging said ratchet-wheel, a connecting-rod, connections between said connecting-rod, pawl and arm, a pawl engaging said ratchet-wheel and attached to a stationary support, and a can-actuated member serving to actuate said connecting-rod.
